Inventor

Henry C. Keeler

By T. P. M. Elroy
his Attorney

UNITED STATES PATENT OFFICE.

HENRY C. KEELER, OF RETSIL, WASHINGTON.

LOCK FOR VALVES.

Application filed April 27, 1920. Serial No. 376,950.

To all whom it may concern:

Be it known that I, HENRY C. KEELER, a citizen of the United States, residing at Retsil, in the county of Kitsap and State 5 of Washington, have invented certain new and useful Improvements in Locks for Valves, of which the following is a specification.

This invention relates to improvements in locks for valves and comprises a housing adapted to be placed in a pipe line intermediate its supply and discharge, means within the housing for controlling the supply through the pipe line, a lock casing 10 in said housing, a lock shaft operating said controlling means, tumblers controlling the movements of said lock shaft and a key adapted to pass through the casing and the housing and release the tumblers and oscillate or rotate the lock shaft for operating the controlling means. The invention further comprises a series of tumbler openings and tumblers in the lock casing and corresponding openings in the lock operating 15 shaft, so arranged that the tumblers can be interchanged to employ any number of tumblers in different openings, thus making a large number of combinations, each combination requiring a different key to operate 20 the lock, all as more fully hereinafter set forth and as claimed.

The invention further comprises a simple and effective lock comprising a small number of inexpensive parts. While I shall describe 35 the lock as particularly applicable to valves for automobiles, it may be used in connection with other devices.

In the accompanying drawings showing 40 one form or specific embodiment of my invention,

Fig. 1 is a side elevation of a carburetor showing in section my improved lock and valve in the pipe line leading thereto;

Fig. 2 is a perspective view of the key, 45 lock, cylinder and valve in their separated relation and removed from the housing;

Fig. 3 is an enlarged horizontal transverse sectional view, taken on the line 3—3 of Fig. 1;

50 Fig. 4 is an enlarged horizontal transverse sectional view, taken on the line 4—4, Fig. 1;

Fig. 5 is an enlarged horizontal sectional view of the lock taken on line 5—5 of Fig. 1 and looking upwardly; 55

Fig. 6 is an enlarged vertical sectional view taken through the lock;

Fig. 7 is a transverse horizontal sectional view taken on the line 7—7, of Fig. 9;

Fig. 8 is an enlarged horizontal transverse sectional view taken on the line 8—8, Fig. 6;

Fig. 9 is an enlarged vertical sectional view showing the tumblers locking the valve operating stem against rotation. 65

Referring now to the drawings, 1 represents a carburetor of a gas engine having the usual intake connection 2 to which my improved combined valve and lock housing 3 is connected in any desired manner, but 70 preferably by the screw-threaded connection 4 as shown in Fig. 1 of the drawings. The housing 3, as shown, is of a cylindrical form having its bottom conical shaped as indicated at 5 and into close fit with the conical 75 valve 6, controlling the passage of oil from the housing through the passage 7 to the carburetor. The valve 6 is provided in its lower wall, with a passage 8 adapted to register with the passage 7 leading to the 80 carburetor and with the passage 9 leading through the nipple and to which is connected a pipe 10 leading from the vacuum tank or the gravity feed oil supply of the automobile. The valve housing above its 85 conical bottom has secured therein a lock casing 11 (hereinafter described) which has its upper end provided with a lateral flange 12 resting upon the annular seat 13 formed on the interior of the valve housing 3 which 90 is formed by the reduced portion 14. The said reduced portion above the lock casing is provided with internal threads 15 into which is secured the plug 16. This plug, as shown, rests upon the upper face of the 95 lock casing 11 and holds the same in engagement with the upper face of the valve 6, whereby it is tightly held on its seat. The plug 16 is held against removal by the transverse pins 17 passing through the valve 100 housing whereby the removal of the plug is prevented so that unauthorized persons cannot remove the lock casing from the housing and operate the valve. The plug

is provided with an enlarged central opening 18 to allow the insertion of the key 19 carrying the oppositely disposed lugs or fins 20. This insures the key being inserted in the proper position to operate the specific predetermined combination as will be later described.

The lock casing, as shown, comprises a cylinder body portion 11 having a central 10 enlarged bore 21 extending from its upper end to a point below the center; the casing also has a reduced opening 22 communicating therewith and extending through the bottom leaving the thick wall 23 surrounding the same. This wall 23 is provided with a series of cylindrical holes 24 communicating with the bottom 25 of the bore 21. I have shown eight of these holes which will make a great number of combinations but 20 the same can be increased or decreased as later described without departing from my invention. Extending through the opening 22 is a shaft or rod 26 which has its lower end squared or angular and adapted to fit 25 into a recess 27 in the valve 6 whereby said valve is rotated therewith. The valves being enclosed in the housing can only be rotated by means of the shaft or rod 26.

Within the holes 24 are the sliding tumblers 28 which are of a cylindrical form closely fitting the walls of the openings and normally pressed upwardly by the springs 29, as shown in Figs. 6 and 9. The shaft or rod 26 about midway its length is provided 35 with an annular flange 30 resting on the bottom 25 with its periphery closely fitting against the bore 21. The lower face of this flange 21 is provided with a series of openings 31 registerable with the holes 24 and 40 of a size to allow the tumblers 28 to enter the same. The tumblers are limited in their upward movement by providing reduced openings as at 32 and communicating therewith are the reduced openings 33 extending through the upper face of the flange. While I have shown eight recesses for the tumblers and eight openings in the flange 21 it is understood that it is not necessary 45 that eight tumblers be used in each lock but one or more tumblers could be used and in such an event the recesses 31 in the flange 30 which have no tumblers below them may be plugged or may be omitted.

The casing 11 is closed by a cap 34 held 50 thereon by means of a screw 35 and said cap is provided with a central opening 36 of a size larger than the diameter of the shaft 26, which extends up therethrough and is flush with the upper face of the cap. This arrangement leaves an annular space around the shaft to allow the hollow key 19 to pass 55 down over the shaft within the casing. The cap 34 is provided with slots 38 communicating with the central opening to allow the fins 20 carried by the key to pass there-

through. The fins 20 are positioned on the key 19 at such points that when (as herein-after described) the upper ends of the fins will engage the under side of the cap and the key will be held in its depressed position. These fins are also for the purpose of allowing or assuring the proper insertion of the key to strike or operate the specifically arranged tumblers which will be later described. The key 19 as shown is of a sleeve-like form and is provided at its lower end with projections 40 adapted to enter the contracted openings 33 in the disks whereby the tumblers can be forced from the recesses 31 flush with the lower face of the flange 30 so that the same can be rotated. The rotation of the disk or shaft is accomplished by providing a fin 41 carried by the shaft 26 above the disk 21 and adapted to enter a slot 42 in the lower edge of the key 19, thus 70 relieving the tumbler operating projections from any strain of the turning operation. The upper end of the key may be made in any desired form to provide the necessary gripping surface to enable the key to be turned.

In operation the key is inserted in the casing surrounding the rotating member, 26, the fins 20 assuring that the projections 40 carried by the lower end of the key will enter the openings in the flange 30 to force the tumblers down. The continued downward movement of the key forces the tumblers below the lower face of the flange. In this downward movement the fins 41 on the shaft 26 has entered the slot 42 in the lower end of the key and upon the rotation of the key the disk is rotated by this engagement. The rotation of the flange rotates the member 26 which in turn rotates the valve 6 thus allowing the liquid to pass through the pipe line as heretofore described. In different locks the tumblers are arranged in different openings and the key is arranged with projections to correspond to the number and spacing of the tumblers. The remaining openings in the disk are plugged or dispensed with. By using one or up to eight tumblers and corresponding projections on the keys there are 312 combinations, it being understood that this number of tumblers could be increased or decreased. In manufacture I usually make standard locks with about eight holes for the tumblers and plug different ones and arrange the tumblers in certain combinations and supply with each lock a corresponding key.

What I claim is:

1. A lock of the character described, comprising a casing, a rotary controlling member therein and extending through the lower end of the casing, a flange carried by said member and having a series of openings therethrough, spring pressed tumblers carried by the casing and entering the openings

from below, and a key having projections entering the openings from the upper side and forcing the tumblers from within the openings in the rotating member and said 5 key having interlocking connection with the rotating member for rotating the same.

2. A lock of the character described comprising a casing, a rotary controlling member therein and extending through the lower 10 end of the casing, a flange carried by said member and having a series of openings therethrough, spring pressed tumblers carried by the casing and entering said openings from below, and a key adapted to slide over 15 the controlling member and having projections on its lower end adapted to enter the openings from the upper side and force the tumblers from within the openings in the flange and a pin carried by the rotary member for entering a notch in the lower end of 20 the key whereby the rotary member is rotated thereby.

3. A lock of the character described comprising a casing, a rotary controlling member therein and extending through the lower 25 end of the casing, a flange carried by the rotary controlling member intermediate the upper and lower ends of the casing, and having vertical openings therethrough having 30 reduced upper ends, spring pressed tumblers carried by the casing and entering the lower end of the openings, a cylindrical sleeve like key passing over the upper end of the rotary controlling member and having projections 35 entering the openings and forcing the tumblers below the lower face of the flange, interlocking means between the key and the rotary operating means for rotating the same and cooperating positioning means between the key and the casing whereby the 40 projections will enter the openings for releasing the tumblers.

4. A lock of the character described comprising a casing, a cover closing the upper end thereof and having a central opening therein, a rotary controlling member in the casing and of a diameter less than the opening in the cap, a flange carried by the member intermediate the upper and lower ends 50 of the casing and having a series of vertical circumferentially arranged openings therethrough having reduced upper ends, said casing having a series of circumferentially arranged recesses adapted to register with 55 the openings in the flange, spring pressed tumblers in said recesses and adapted to be normally held upwardly within the end of the openings in the flange, a cylindrical sleeve like key passing over the upper end of 60 the rotary controlling member and having projections entering the openings in the flange for forcing the tumblers below the lower face of the flange, interlocking means between the key and the rotary member for 65 rotating the same, and cooperating position-

ing means between the key and the casing whereby the projections will enter the openings carrying the tumblers.

5. A lock of the character described, comprising a casing, a controlling shaft therein 70 and connected to the movable member to be operated, a flange carried by the controlling shaft intermediate its ends, tumblers in the casing and entering openings in the flange, a key adapted to slide over the controlling 75 shaft and having projections adapted to enter the openings in the flange and force the tumblers therefrom and allow the shaft to be rotated, and interlocking means between the lower end of the flange and the 80 key whereby the flange is rotated.

6. A lock of the character described, comprising a casing, a controlling shaft thereon and connected to the movable member to be operated, a flange carried by said controlling 85 shaft intermediate its ends, spring pressed tumblers in the casing and normally entering openings in the flange, a hollow key adapted to receive the shaft and having projections adapted to enter the openings in the 90 flange and force the tumblers therefrom and allow the shaft to be rotated and interlocking means between the flange and the lower end of the key whereby the flange is rotated by the key. 95

7. A lock of the character described comprising a casing, a controlling shaft therein, and connected to the movable member to be operated, a flange carried by the controlling shaft and having a series of openings, spring 100 pressed tumblers carried by the casing and entering some of said openings, and a key having projections at its end to enter a series of said openings in the flange, means carried by the casing for causing the projections to enter the openings with the tumblers therein whereby the tumblers are forced from the flange and the shaft rotated and interlocking means between the flange and the lower 105 end of the key whereby the flange is rotated. 110

8. A lock of the character described comprising a casing, a controlling shaft therein and connected to the movable member to be operated, a flange carried by the controlling shaft and having a series of openings, spring 115 pressed tumblers carried by the casing and entering some of said openings and a key having a number of projections less than the number of openings in the flange and means carried by the casing for guiding the key so that the projections on the key will enter the openings carrying the tumblers whereby the tumblers are forced from the flange and the shaft rotated by the key. 120

9. A lock of the character described comprising a casing a controlling shaft therein and connected to the movable member to be operated, a flange carried by the controlling shaft intermediate its ends, tumblers in the 125 casing and entering some of the openings in 130

the flange, a key of a cylindrical form to receive the shaft and having projections at its lower end arranged to enter the openings in the flange in which the tumblers are arranged and means carried by the casing for properly guiding said key so that the projections will enter the proper openings in the flange and interlocking means between the lower end of the key and the flange 10 whereby the flange is rotated by the key.

10. A lock of the character described comprising a casing a controlling shaft therein and connected to the movable member to be operated, a flange carried by the controlling

shaft intermediate its end and having a series of openings, tumblers in the casing and entering some of the openings in the flange, and a key of a cylindrical form to receive the upper end of the shaft, projections carried by the lower end of the key and of a less number than the openings in the flange and adapted to enter the openings carrying the tumblers, means for properly guiding the key, and interlocking means between the key and shaft for rotating the same. 15 20 25

In testimony whereof, I affix my signature.

HENRY C. KEELER.
